CLAIM

The ornamental design for a motor vehicle and/or toy vehicle replica, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a left, front perspective view of a motor vehicle and/or toy vehicle replica showing our new design;

FIG. 2 is a left, rear perspective view thereof;

FIG. 3 is a front elevation view thereof;

FIG. 4 is a rear elevation view thereof;

FIG. 5 is a left side elevation view thereof;

FIG. 6 is a right side elevation view thereof; and,

FIG. 7 is a top plan view thereof.

The bottom view of the motor vehicle and/or toy vehicle replica forms no part of the claimed design. The broken lines in FIGS. 1-7 depict boundaries around de-emphasized elements, which illustrate portions of the motor vehicle and/or toy vehicle replica which form no part of the claimed design.
